UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,186, dated March 15, 1881.

Application filed February 7, 1881. Term of patent 3½ years.

To all whom it may concern:

Be it known that I, HENRY HORAN, of East Orange, county of Essex, and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a flower group, composed of the figure G, consisting of two open roses with their surrounding leaves, of the figure I, a branch with leaves and rose-buds thereon, of the figure K, a tendril with a rose thereon, of the figure R, a flowering branch, of the figure H, containing leaves and projecting flowers, and of the figure E, composed of circular flowers, with moss-like foliage around them, all the other figures projecting from the central figure, G.

The figure D is a bunch of pointed leaves with flowers between them.

The figure C is a bunch of leaves and flowers somewhat like D.

B is a flower group, composed of the cluster of round and pointed leaves L, and of the flower-spray S, and of the cluster of flowers M, resembling pinks.

The background is formed of figures P, containing a square pattern alternating with figures O, containing a rectangular Grecian pattern, the effect being somewhat like that of a checker-board.

The whole effect of the design is that of the checkerboard background, with the flower groups and figures described set upon it in regular order,

I claim—

1. The design for carpets, consisting of the groups A, composed of figures G I K R H E, substantially as shown.
2. The design for carpets, consisting of the figure G, substantially as shown.
3. The design for carpets, consisting of the figure I, substantially as shown.
4. The design for carpets, consisting of the figures K and R, substantially as shown.
5. The design for carpets, consisting of the figure H, substantially as shown.
6. The design for carpets, consisting of the figure E, substantially as shown.
7. The design for carpets, consisting of the figures G and I, substantially as shown.
8. The design for carpets, consisting of the figure D, substantially as shown.
9. The design for carpets, consisting of the figure C, substantially as shown.
10. The design for carpets, consisting of the figures O and P, substantially as shown.
11. The design for carpets, consisting of the group B, composed of the figures L, S, and M, substantially as shown.
12. The design for carpets, consisting of the figure L, substantially as shown.
13. The design for carpets, consisting of the figure M, substantially as shown.
14. The design for carpets, consisting of the group A, composed of figures G I K R H E, group B, composed of figures L S M and figures C D O P, substantially as shown.

HENRY HORAN.
